UNITED STATES PATENT OFFICE

2,309,486

SCREENING APPARATUS

Don A. Weber, Fort Wayne, Ind., assignor to The
Deister Concentrator Company, Fort Wayne,
Ind., a corporation of Indiana

Application May 15, 1939, Serial No. 273,712

3 Claims. (Cl. 209—365)

This invention pertains to screening apparatus, more particularly of the type in which a screen cloth or fabric is vibrated in a direction normal to the plane of its surface, so as to agitate the material on the screen in order to cause the fine grains to pass through the screen and the coarser grains to move therealong.

A usual construction of such screening apparatus involves a frame in which the screen fabric is tensioned so as to hold it taut in the desired position. In this type of apparatus vibrating mechanism is often mounted upon a bridge which spans the above mentioned frame, and a connection extends from the vibrating mechanism to the screen fabric in order to transmit the vibrating movement to the latter. It has been found that the structure of such a bridge is sometimes sufficiently flexible to cause the same to give slightly under the forces necessary to vibrate the screen, and that accordingly the vibratory motion imparted to the screen does not conform exactly to that set up by the vibrating mechanism.

An object of this invention, therefore, is to provide a bridge structure which will be extremely rigid so that the vibratory movement may be transmitted to the screen fabric with increased accuracy.

It is also found that the structures which have been used for mounting the vibrating mechanism, which are usually of cast iron, are often subject to shocks during shipment of the apparatus, and that castings are broken.

Another object of this invention, therefore, is to provide an improved bridge structure which will not only have improved rigidity, but which will be capable of protecting the support for the vibrating mechanism against accidental injury.

Another object is to provide a bridge structure in which the structure of the housing or support for the vibrating mechanism is included so as to provide not only mechanical protection for such housing, but cooperative bracing so as to additionally support and brace the bridge structure.

Further objects will appear from the following description, taken in connection with the accompanying drawings, in which Figure 1 is a longitudinal section of a screening apparatus embodying this invention. Figure 2 is a section on line 2—2 of Figure 1 showing a rear view of the bridge. Figure 3 is a horizontal section somewhat enlarged of the middle portion of the bridge structure taken just below the removable cover. Figure 4 is a similarly enlarged section

taken about on line 4—4 of Figure 2. Figure 5 is an enlarged detail of Figure 1 and Figure 6 is a side view to a reduced scale of a complete screening apparatus embodying this invention.

5 In the apparatus selected for illustration of the invention in the accompanying drawings a screen frame 1 is mounted at any suitable angle in a support 2. Any suitable adjusting device 3 may be provided to adjust the angle 10 at which the frame 1 is set. A screen cloth or fabric 4 is stretched within the frame 1 by means of any suitable tensioning devices 5. The screen fabric 4 may be of any type suitable for operation on the particular material to be handled. For coarser materials the screen fabric may be constructed of a sheet of perforated steel or other suitable metal. For finer materials woven wire cloth may be used.

20 Mounted on a bridge indicated generally at 6 is a vibrating mechanism of any suitable type indicated generally at 7. This vibrating mechanism may be of the type described in detail in Patent No. Re. 16,701, issued to Richard A. Leahy, and Patent No. 1,712,817, issued to Victor E. Flanagan. From this mechanism a connection shown in the drawings as a rod or stem 8 extends from the vibrating mechanism 7 to the screen fabric 4 and is connected to the latter in any suitable manner so as to transmit the vibratory movement from the mechanism 7 to the screen fabric. In the structure illustrated in the drawing the connection to the screen fabric 4 is made through a frame or panel 9. The structure of this panel and its 25 operation in connection with the screen fabric is described in detail in the co-pending application of Don A. Weber and Spencer A. Stone, issued as Patent No. 2,250,737 on July 29, 1941. The vibrating mechanism may be driven by 30 any suitable driving means such as a motor 10. In lieu of a motor such as 10 the shaft 70 of the mechanism 7 may be extended outwardly from the bridge 6 and provided with a pulley or other device adapted for driving the same from 35 some external source of power.

The structure of the bridge 6 comprises a pair of side members 11 extending substantially parallel to each other and so as to span the frame 1. The members 11 are spaced apart a suitable distance so as to accommodate between them a floor member 12. The members 11 and 12 may be secured together by any suitable means as, for instance, by welding. In the structure illustrated they are additionally reinforced by angle 40 members 13 extending preferably the full length

of the bridge 6 between the sides of the frame 1. This provides for the bottom of the bridge a channel or boxed structure forming a stiff and rigid bridge, both vertically and laterally. The ends of this boxed structure may be stiffened by transverse angles 14 extending between the side members 11 and secured thereto and to the members 12 and 13 in any suitable manner as, for instance, by welding. All these parts of the bridge are preferably constructed of wrought metal, such as steel plate and angles. The middle portions of the members 11 extend upwardly from the ends so as to have a considerable height at the middle portion. This, of course, renders these side members very stiff in the vertical direction.

The vibrating mechanism 1 may be supported and housed in an inner housing 15 of appropriate form to enclose the mechanism. A suitable form for this housing is described in the above mentioned Patent No. 1,712,817. This housing may be filled with oil so as to lubricate the vibrating mechanism.

In accordance with this invention the housing 15 is provided with extended end members 16 forming a part of the housing 15 and extending across the space between the members 11. The housing 15 is preferably mounted in the middle portion of the bridge 6 so as to be supported by the bridge, and the end members 16 are provided with lugs 17 to accommodate fastening means for securing these end members to the side members 11. Such fastening means may be bolts 18 or other suitable devices. This arrangement secures the upper portions of the side members 11 rigidly together, the members 16 of the inner housing serving to brace the members 11 rigidly so that the entire bridge forms a rigid truss or braced structure. It will be noted that the housing 15, which is usually a casting of cast iron or other suitable material, is enclosed between the side members 11 so as to be protected thereby against injury from the outside.

In order to provide for access to the housing 15 and the vibrating mechanism contained therein, one of the members 11 is provided with an opening 19 which may be closed by a movable cover 20 of suitable design. In the embodiment illustrated the cover 20 is formed of a sheet metal plate of the same gauge as that of the side members 11 bent to angular form to provide a top plate 21 and a rear plate 22. The top plate 21 may have secured thereto as by welding a pair of pins 23 so located as to enter drilled holes 24 in the rear side member 11. When the pins 23 are inserted in the holes 24 the cover may be lowered so as to fit the front plate 22 into the opening 19. This completes an outer enclosure formed by the cover 20, the side members 11 and the end members 16 within which the inner housing 15 is enclosed. The front plate 22 may be provided with a lug or plate 25 having a slot 26 adapted to receive a clamping bolt 27 swiveled at 28 in the front plate 22 and provided with a hand nut 29 which may be screwed down upon the lug 25 to secure the cover 20 in place.

In order to provide for the passage therethrough of the stem 8, an opening 30 is formed to pass through the bottom of the housing 15 and also the floor plate 12. In order to render the outer enclosure formed by the plates 11, and the end members 16 dust proof, a suitable fitting 31 may be placed around the opening 30 and a flexible sheet of rubber or other suitable material 32 may be placed over said fitting and secured by 33 plate, a pair of upright cross webs extending be-

5 a suitable clamping ring 33. The plate or disc 32 may have a close fit upon the stem 8 so as to prevent the passage of dust therealong, and its flexibility permits it to vibrate with said stem, while at the same time maintaining a dust proof closure.

10 It will be seen, therefore, that this invention provides an improved structure for this type of bridge. The arrangement of the trussed structure of the bridge itself is such as to provide a very stiff and rigid support for the vibrating mechanism. The lower channel structure is surrounded by the upwardly extending side members 11 which, on account of their height at the middle, have the stiffening effect of a high upper chord for a truss. These plates are rigidly side braced by the members 16 extending between them and rigidly secured to them. This prevents any side sway or any tendency for the truss structure to twist. In the vertical direction the bridge is particularly stiff and, therefore, provides an advantageous support for a vibrating mechanism of the type mentioned as a characteristic of the operation of such mechanism is that it must impart very sudden movements to the screen fabric in order to provide a throwing action tending to throw the particles of material upwardly from the screen so as to facilitate their movement therealong. With such mechanism the extra rigid bridge structure is effective in imparting such movement accurately without any give or yielding when the sharp increase in force must be transmitted.

15 It will be noted also that the structure provides a double enclosure for the vibrating mechanism. The inner enclosure 15 houses the mechanism itself and provides for immersion thereof in oil. The outer housing provides not only mechanical protection to the inner housing, but also additional dust proofing. The greater portion of the dust is excluded by the outer housing so as to prevent the collection of dust on the inner housing which usually promotes the gradual entrance of dust particles into the housing through cracks around the openings for the shaft and vibrating

20 levers.

25 While the invention has been described as embodying a unitary structure, it will be understood, of course, that individual features or subcombinations thereof may be useful by themselves 30 without reference to other features or the complete combination, and it is understood that the employment of such individual features or subcombinations is contemplated by this invention as within the scope of the appended claims.

35 It is further obvious that various changes in the details of construction within the scope of the appended claims may be made without departing from the spirit of this invention, and that accordingly the invention is not limited to the specific 40 details shown or described.

45 Having thus described the invention what is claimed is:

50 1. Drive mechanism for screening apparatus of the character described having a screen supported on a stationary frame for vibratory movement, comprising, a built-up structure spanning the stationary frame, said structure including a pair of upright sheet-metal side plates, a horizontally-extending sheet-metal floor plate extending between and spacing said side plates, means rigidly connecting said side and floor plates, stiffened end braces extending between and secured to said side plates and to said floor 55 plate, a pair of upright cross webs extending be-

tween and secured to said side plates at spaced points near the middle thereof, thereby forming with the said side plates a compartment, a top closure for said compartment, an enclosed oil-bath mounted within said compartment, and a vibrating mechanism in said oil-bath and connected to vibrate the screen.

2. Drive mechanism for screening apparatus of the character described having a screen supported on a stationary frame for vibratory movement, comprising, a built-up structure spanning the stationary frame, said structure including a pair of upright sheet-metal side plates, a horizontally-extending sheet-metal floor plate extending between and spacing said side plates, means rigidly connecting said side and floor plates, stiffened end braces extending between and secured to said side plates and to said floor plate, a pair of upright cross webs extending between and secured to said side plates at spaced points near the middle thereof, thereby forming with said side plates a compartment, and vibrating mechanism in said compartment connected to vibrate the screen.

3. Drive mechanism for screening apparatus of the character described having a screen supported on a stationary frame for vibratory movement, comprising, a built-up structure spanning the stationary frame, said structure including a pair of upright sheet-metal side plates, a horizontally-extending sheet-metal floor plate extending between and spacing said side plates, means rigidly connecting said side and floor plates, 10 stiffened end braces extending between and secured to said side plates and to said floor plate, a vibrating unit having vibrating mechanism and a housing therefor, said housing having outwardly extending webs, said webs being positioned to extend between said side plates and being secured thereto, thereby forming between said webs and said side plates a compartment enclosing said unit, a top closure for said compartment, and connections from said vibrating mechanism to 15 20 vibrate the screen.

DON A. WEBER.
